UNITED STATES PATENT OFFICE.

SAMUEL A. CLAGGETT AND SAMUEL DEVALL, OF LOS ANGELES, CALIFORNIA.

DESIGN FOR A SOUVENIR-BADGE.

53,486.

Specification for Design.

Patented July 8, 1919.

Application filed March 6, 1918. Serial No. 220,877. Term of patent 7 years.

To all whom it may concern:

Be it known that we, SAMUEL A. CLAGGETT and SAMUEL DEVALL, citizens of the United States, residing at Los Angeles, in the county of Los Angeles and State of California, have invented a new, original, and ornamental Design for a Souvenir Badge, of which the following is a specification, reference being had to the accompanying drawing, forming a part thereof.

Figure I is a perspective of a souvenir badge, showing our new design; and Fig. II is a rear perspective of the same.

We claim:

The ornamental design for a souvenir badge, as shown.

SAMUEL A. CLAGGETT.
SAM DEVALL.
